TAPE ROLL SUPPORTING MEANS.

Arthur T. Hart, York, S. C.

Application September 7, 1948, Serial No. 48,059

1 Claim. (Cl. 242—55.2)

1

This invention relates to an auxiliary tape supporting means for adding machine and the like.

Heretofore most adding machines and the like have been provided with a pair of upwardly extending ears having a shaft mounted therein and on which a conventional roll of adding paper tape has been rotatably mounted. However, there are many instances in which adding machines are used where the maximum possible diameter of the roll of tape on the adding machine has been restricted to such an extent that it has been necessary to install a roll of tape several times on the adding machine during a single working period, such as banking and the like, which not only interrupts the sequence of the numerals marked on the tape by the adding machine, but also takes a considerable amount of time as well as being inconvenient to the operator of the adding machine.

It is therefore an object of this invention to provide a pair of arms, one of the ends of which may be mounted on the existing shaft in the adding machine on which the original sized roll of tape has heretofore been mounted, and the opposite ends of the arm having a shaft therebetween on which a roll of tape of much greater diameter may be rotatably mounted, and to further provide an adjustable bracing member, one end of which is secured to the medial portions of the arms and this bracing member extends downwardly from the arms and may rest against the housing of the adding machine, or in the instance of the adding machine being mounted on a stand, the lower edge of the bracing member may have a transverse bar secured to the same which is adapted to engage the legs of the frame on which the adding machine is mounted, thus serving to support the other end of the arms between which the paper tape is mounted.

Some of the objects of the invention having been stated, other objects will appear as the description proceeds, when taken in connection with the accompanying drawings, in which

Figure 1 is an isometric view of an adding machine showing the invention applied thereto and an enlarged roll of paper tape mounted thereon;

Figure 2 is an isometric view of the frame on which the enlarged roll of paper is mounted and showing a portion of an adding machine in dotted lines and is taken on an enlarged scale;

Figure 3 is an isometric view of another type of adding machine mounted on a stand and showing a modified form of the invention;

Figure 4 is an enlarged isometric view of the

2

modified form of the invention shown in Figure 3, but showing the same removed from the adding machine;

Figure 5 is a vertical sectional view taken along the line 5—5 in Figure 4;

Figure 6 is an isometric view of still another modified form of the invention and showing a portion of an adding machine in dotted lines.

Referring more specifically to the drawings,

10 Figure 1 shows an adding machine of the type to be mounted on a table or the like and this adding machine is conventional in all respects, and comprises a housing 10 having a keyboard 11, an operating handle 12, a tabulating carriage 13 and a conventional platen 14 for feeding the conventional tape therearound. The adding machine also has a casing 15 which encloses conventional type bars 16 and it is a well known fact that upon depressing the desired keys on the keyboard 11 and moving the handle 12 downwardly about its axis, the type bars 16 in the casing 15 are caused to move forwardly and upwardly selectively, thus marking the desired figures on the adding machine tape.

15 20 25 Now, this machine has a conventional U-shaped member 17 mounted thereon which is penetrated by a conventional bolt 18 having a conventional roller 20 rotatably mounted thereon. This roller 20 normally carries the conventional size roll of paper tape.

20 25 30 The enlarged paper roll, indicated at 25 in Figure 1, is wound about a conventional core 26 rotatably mounted on a spacer sleeve 27 which is a part of the paper supporting frame broadly designated at 30. The paper supporting frame 30 comprises arms 31 and 32 (Figure 2), the left-hand ends in Figures 1 and 2 of which are pivotally mounted on the bolt 18 and attention is called to the fact that one of the arms 31 or 32

35 40 45 is adapted to be mounted between one of the upwardly extending ears of the U-shaped member 17 and one end of the roller 20 on the bolt 18, and the proximate side of the other of the arms 31 or 32 is adapted to engage the remote side of the other ear of the U-shaped member 17 and is engaged at its remote surface by the head of the bolt 18 to thus secure the arms 31 and 32 of the frame 30 to the U-shaped member 17.

45 50 The reason the arms 31 and 32 are so mounted on the bolt 18 is so that the edge of the paper tape 25 nearest the observer in Figures 1 and 2 as it passes over the roller 20 may pass closely adjacent the vertical ear of the member 17 nearest the observer in Figure 1 thereby permitting the tape from the enlarged roll 25 to be aligned

55

properly with the type bars 16 so this edge of the paper will pass through the same path as that edge of the paper would pass were the smaller size conventional roll of paper mounted on the roller 20 in the conventional manner.

The free ends of the arms 31 and 32 are held apart from each other by the sleeve 27 and penetrating the sleeve 27 as well as the free ends of the arms 31 and 32 is a bolt 35 thus securing the arms 31 and 32 to the ends of the sleeve 27.

The arms 31 and 32 have a plurality of bores 36 penetrating the same and these arms 31 and 32 are countersunk on the proximate sides thereof for receiving the head portions of bolts 37. The bolts 37 secure the upper ends of diverging arms 40 and 41 of a substantially U-shaped member 43 to the remote sides of the arms 31 and 32. The lower ends of the diverging arms 40 and 41 are bridged by a lateral portion 42 integral therewith. This lateral portion 42 has bores 45 therein (Figure 2) which may be used, if so desired, for inserting suitable screws or bolts therein for securing the lateral portion 42 of the U-shaped member 43 to the housing 10 of the conventional adding machine. However, it may be observed in Figures 3 and 4 that these bores 45 in the lateral portion 42 of the U-shaped member are penetrated by screws 47 which are threadably imbedded in a bar 50 extending outwardly from each side of the U-shaped member 43, for the purpose to be later described.

Referring to Figure 3, there may be observed an adding machine having a stand integral therewith. The upper portion of this adding machine is identical to that shown in Figure 1, and therefore like reference characters will apply to like parts, with prime notation added, however, in this instance, the adding machine has projections 51 and 52 on the rear end thereof which support a rod 53 and oscillatably mounted on the rod 53 is a bracket 54 which is conventional and which has spaced transverse rods 55 and 56 therein and the free end of the bracket 54 has a transverse roller 57 mounted therein which is normally rotatably mounted on a screw 58. This roller 57 has heretofore carried the roll of paper tape, the diameter of the roll of paper necessarily being restricted due to the limiting features of the bracket 54, such as the transverse rods 55 and 56. In this instance the adding machine is supported on vertical legs 60, 61, 62 and 63. The frame 30 for carrying the enlarged roll of paper tape 25 is mounted on the type of machine shown in Figure 3 in an identical manner to which it is mounted on the type of machine shown in Figure 1, with the exception that the left-hand ends of the bars 31 and 32, in Figures 3 and 4, are mounted on the bracket 54 and are penetrated by bolt 58, the sleeve 56 engaging the proximate side of one of the bars 31 or 32 and the proximate side of the other of the bars 31 or 32 engaging the side of the bracket 54 remote from the sleeve 56 and the remote side of this arm being engaged by the head of the bolt 57 to thus secure the frame 30 to the bracket 54. It may be observed in Figure 3 that the bar 50 that extends outwardly beyond each side of the U-shaped member 43 is adapted to support the weight of the frame 30 and the associated roll of paper tape 25 as it

engages the vertical surfaces of the legs 62 and 63.

There are more than one of the bores 36 in each of the arms 31 and 32 to thereby permit the arms 40 and 41 of the U-shaped member 43 to be adjusted relative to the arms 31 and 32 and to accommodate various types and shapes of adding machines, the adding machines shown in the drawings being typical and being shown by way of illustration only.

Figure 6 shows another modified form of the invention which is identical with the first two forms of the invention, with the exception of a U-shaped brace member broadly designated at 70, and therefore parts of the structure shown in Figure 6 shall bear the same reference characters as identical parts in Figures 1 to 5 inclusive. The U-shaped brace member 70 is similar to the U-shaped member 43 with the exception that instead of being comprised of diverging arms, the U-shaped member 70 has parallel spaced arms 71 and 72, the lower ends of which are bridged by a lateral portion 73 integral therewith. The lateral portion 73 has bores 74 therein which are provided for the same purposes as the bores 45 in the U-shaped member 43. The bolts 37 also secure the U-shaped brace member 70 to remote sides of the arms 31 and 32 in the same manner in which they secure the U-shaped member 43 to the same in the first two forms of the invention.

In the drawings and specification there has been set forth a preferred embodiment of the invention, and although specific terms are employed, they are used in a generic and descriptive sense only, and not for purposes of limitation, the scope of the invention being defined in the claim.

I claim:

40 In an adding machine, a housing, a pair of spaced parallel members secured to and extending from the housing, a pair of spaced outwardly extending arms pivotally connected to the spaced parallel members, a transverse spacer disposed between the free ends of the outwardly extending arms adapted to support a roll of tape, a substantially U-shaped member comprising a horizontal bar, the opposite ends of which are bent upwardly at right angles to the horizontal bar to form two parallel spaced arms, means pivotally connecting the upper ends of each of said arms of said U-shaped member to a medial portion of each of the outwardly extending arms and the horizontal bar of the substantially U-shaped member being adapted to engage the housing for supporting the said outwardly extending arms and the roll of tape mounted therebetween.

ARTHUR T. HART.
